A. D. HOSFELDT,
PAPER ROLL FIXTURE,
APPLICATION FILED OCT. 12, 1917.

1,310,019.

Patented July 15, 1919.

UNITED STATES PATENT OFFICE.

ARTHUR D. HOSFELDT, OF PORTLAND, OREGON.

PAPER-ROLL FIXTURE.

1,310,019.

Specification of Letters Patent. Patented July 15, 1919.

Application filed October 12, 1917. Serial No. 196,337.

To all whom it may concern:

Be it known that I, ARTHUR D. HOSFELDT, a citizen of the United States and a resident of the city of Portland, county of Multnomah, State of Oregon, have invented a certain new and useful Improvement in Paper-Roll Fixtures, of which the following is a specification.

This invention relates to wall fixtures, such as adapted for rotatably supporting a roll of toilet paper, or paper towels. My invention has for its object the providing of a simple, inexpensive device for said purpose. Furthermore, to induce by my fixture the more economical use of paper by preventing the wasteful tearing off of longer strips than to be used; this result being attained by requiring each sheet to be torn off separately. Furthermore, my invention has for its purpose the providing of a fixture which is adjustable to rolls of varying length.

I attain these objects, and incidental features, in the device illustrated in the accompanying drawings, of which:

Figure 1 represents my fixture as appearing when supporting a roll of paper, the end of which is positioned as required for tearing off;

Fig. 2 is a front elevation of my fixture with parts broken away and other parts shown in section; and

Figs. 3 to 8 inclusive illustrate details of construction hereinafter fully described.

My invention comprises a U-shaped bracket *a*, the sides *a'* of which is made with a hole to receive one end of a shaft *b*; rotatably supported by the bracket; and the side *a²* of the latter is provided with a slot *a³*, in which to removably insert the related end of the shaft *b*. To hold the latter against longitudinal movement the end *b'* is provided with a peripheral groove in which bears a keeper *c* pivoted on a pin *d*. Said keeper is, for convenience, made with a lip, or flange, *c'* so as to facilitate the lifting thereof by the finger, and a spring-controlled latch *e* having a locking pin *e'* (see Fig. 7) holds the keeper *c* in place so as to prevent its accidental lifting. The keeper is made with a lip at its free end, as shown, so as to facilitate the pulling of it outward to pull out the pin *e'*. The shaft *b* is permitted to rotate only in the direction indicated by the arrow in Fig. 1. This result is conveniently accomplished as shown in

Fig. 3, showing an inside view of the side *a'* of the bracket. The related end of the shaft *b* has a fixed ratchet pinion *f* with which engages a pawl *g* pivoted on the reel-side *h*, 60 non-rotatably supported on the shaft *b*. It may be fixed on the latter. The companion reel side *h'* is longitudinally movable on the shaft *b* and secured in place as adjusted by a keeper *i* (see Figs. 1, 2, 5) which is adapted 65 to engage with one of the notches *j* provided in the related end of the shaft *b*, as shown in Fig. 2. That portion of the shaft *b* lying between its ends is preferably made square so as to non-rotatably carry the cone sections 70 *k*, *k'* which are adapted to bear in the hollow core of the roll of paper and thus clamp and rigidly hold the latter. The cone section *k'* is removable and longitudinally adjustable 75 on the shaft *b*, and to this end is provided with a keeper *l*, adapted to be engaged with one of the notches *j* of the shaft *b*, as shown in Figs. 2 and 4.

The reel sides *h*, *h'* carry radially disposed cutter-bars *m*, the upper face of which 80 is serrated or otherwise adapted (as at *m'*) to form an edge upon which to tear off the end of the paper strip. For the purpose of reducing the cost of metal, and also adding neatness to the appearance of my device, 85 I prefer to support the cutter-bars *m* on radially disposed arms *n*, integral with the reel sides *h*, *h'*. The right ends of the cutter bars *m* are removably inserted for removing the core of the used roll of paper and insert a new roll. *o* represents the roll of paper. The free end of the roll of paper *p* must be arranged so as to overlie the cutter bar projecting at the front of my fixture, as shown 90 in Fig. 1. And since the reel can rotate only in the direction indicated by the arrow in Fig. 1, by pulling on the strip end *p* the same is readily detached from the roll. The end of the strip of the roll from which the piece 95 *p* has been torn off will then depend. By seizing such end it may be drawn to the desired length, by the rotation of the reel; then the end is again arranged so as to overlie said cutter bar, and another strip may 100 be torn off the roll.

I claim:

1. A device of the character described comprising a bracket, a reel supported thereby and rotatable in one direction only, 110 one side of the reel being removable, cutter bars radially disposed on the reel sides, and

means for rigidly holding a roll of paper between the reel sides.

2. A device of the character described comprising a bracket, a reel supported thereby and rotatable in one direction only, one side of the reel being adjustable and removable, cutter bars radially disposed on the reel sides, and means for rigidly holding a roll of paper between the reel sides.

10 3. A device of the character described comprising a bracket, a reel supported thereby and rotatable in one direction only, one side of the reel being removable, cutter bars radially disposed on the reel sides, opposed cone sections on said shaft one thereof being removable, and means for securing such cone in place on the shaft.

20 4. A device of the character described comprising a bracket, a reel supported thereby and rotatable in one direction only, one side of the reel being removable, cutter bars radially disposed on the reel sides, opposed cone sections on said shaft one thereof being removable, and means for securing such cone adjustably in place on the shaft.

30 5. A device of the character described comprising a bracket, a reel supported thereby and rotatable in one direction only, one side of the reel being adjustable and removable, cutter bars radially disposed on the reel sides, opposed cone sections on said shaft one thereof being removable, and means for securing such cone adjustably in place on the shaft.

35 6. A device of the character described comprising a bracket, a shaft rotatably supported thereby, means for limiting the rotation of the shaft to one direction, means for holding the shaft against longitudinal movement in its brackets, reel-sides non-rotatably mounted on the shaft, one of such sides being removable, cutter bars, radially disposed on the reel-sides, and means for rigidly holding a roll of paper between said reel-sides.

40 7. A device of the character described comprising a bracket, a shaft rotatably supported thereby, means for limiting the rotation of the shaft to one direction, means for holding the shaft against longitudinal move- 85

45 50

ment in its bracket, reel sides non-rotatably mounted on the shaft, one of such sides being removable and also being longitudinally adjustable on the shaft, cutter bars radially disposed on the reel sides, and means for rigidly holding a roll of paper between said reel sides. 55

8. A device of the character described comprising a bracket, a shaft rotatably supported thereby, means for limiting the rotation of the shaft to one direction, means for holding the shaft against longitudinal movement in its brackets, reel sides non-rotatably mounted on the shaft, one of such sides being removable, cutter bars radially disposed on the reel sides, and opposed cone sections on said shaft one thereof being removable. 60

9. A device of the character described comprising a bracket, a shaft rotatably supported thereby, means for limiting the rotation of the shaft to one direction, means for holding the shaft against longitudinal movement in its brackets, reel sides non-rotatably mounted on the shaft, one of such sides being removable, cutter bars radially disposed on the reel sides, opposed cone sections on said shaft one thereof being removable, and means for securing such cone in place on the shaft. 70

10. A device of the character described comprising a bracket, a shaft rotatably supported thereby, means for limiting the rotation of the shaft to one direction, means for holding the shaft against longitudinal movement in its brackets, reel sides non-rotatably mounted on the shaft one of such sides being removable, cutter bars radially disposed on the reel sides, opposed cone sections on said shaft one thereof being removable, and means for securing such cone adjustably in place on the shaft. 85

11. In a device of the character described, the combination of a supporting bracket, a reel for carrying a paper roll, such reel rotatable in one direction only, and a cutter bar carried by the reel, such bar arranged parallel to the axis of rotation of the latter. 90

ARTHUR D. HOSFELDT.
